UNITED STATES PATENT OFFICE.

ISAAC F. WILLEY, OF PHILADELPHIA, PENNSYLVANIA.

IRONING-MACHINE.

1,256,280.

Specification of Letters Patent. Patented Feb. 12, 1918.

Application filed September 14, 1915. Serial No. 50,596.

To all whom it may concern:

Be it known that I, ISAAC F. WILLEY, a citizen of the United States, residing in the city and county of Philadelphia, State of Pennsylvania, have invented a new and useful Ironing-Machine, of which the following is a specification.

My invention consists of a novel ironing machine which is especially adapted for the ironing of collars. In the machines ordinarily employed for this purpose, it is customary to feed the collars to the ironing rolls in the direction of their length and owing to the distance between the axes of the rolls and the manner in which the collars are pulled by the operator as they are fed into the machine, the original length of a collar is materially increased and the ends and buttonholes are lengthened and distorted in such a manner that the ironed collar does not set properly on the shirt of the wearer, and its natural spring is destroyed.

My present invention has been designed to overcome the above noted defects and the collars are fed into the machine in such a manner that they are presented laterally to the ironing rolls with their entire surface uncovered. The collars are fed laterally or in parallelism with the axes of the ironing cylinder and roll and the direction of movement of the collar is in a continuous forward direction.

My invention further consists of a novel manner of yieldingly mounting the rolls, which coöperate with the main ironing drum so that a uniform tension is placed on such rolls.

It further consists of a novel construction and arrangement of an ironing roll and its adjuncts whereby the amount of effective surface of the ironing roll is largely increased during the ironing operation.

Other novel features of construction and advantage will more clearly hereinafter appear in the detailed description of my invention.

For the purpose of illustrating my invention, I have shown in the accompanying drawings one form thereof which is at present preferred by me, since the same will give in practice satisfactory and reliable results, although it is to be understood that the various instrumentalities of which my invention consists can be variously arranged and organized and that my invention is not

limited to the precise arrangement and organization of these instrumentalities as herein shown and described.

Figure 1 represents a top plan view of a collar ironing machine embodying my invention.

Fig. 2 represents a side elevation thereof having certain portions broken away for the sake of clearness of illustration.

Fig. 3 represents a sectional elevation of the machine, the section being taken on line 3—3 of Fig. 2.

Fig. 4 represents a front elevation of an alining roll for the feed apron.

Fig. 5 represents a sectional elevation of a portion of the machine showing more clearly certain details of construction, the section being taken on line 5—5 Fig. 1.

Fig. 6 represents a sectional elevation showing more clearly details of construction of the feed apron and certain of its adjuncts.

Fig. 7 represents a sectional elevation of a portion of the machine, the section being taken on line 7—7 Fig. 2.

Fig. 8 represents a sectional view of the means for adjusting one of the rolls.

Similar numerals of reference indicate corresponding parts in the figures.

Referring to the drawings:—

1 designates the housing or framework of an ironing machine, embodying my invention, and adapted to be actuated by any desired type of driving mechanism. For convenience of illustration, I have shown a motor 2, such as for example an electric or other motor, carried by the housing and having its shaft provided with a pinion 3, which meshes with a gear 4, mounted on a shaft 5, journaled in the machine framework. The shaft 5 has mounted thereon a gear 6, which meshes with a gear 7, mounted on a shaft 8, journaled in the housing. 9 designates a sprocket wheel mounted on the shaft 8 and provided with a sprocket chain 10, which passes around a sprocket wheel 11, carried by the first ironing roll 12, which latter is mounted in journal boxes 13 adjustably carried by the housing. The ironing roll 12 is in frictional engagement with a feed apron 14, which passes around a front roll 15, the ends of which have loosely mounted thereon the sleeves 16, Fig. 1, the inner ends of which are provided with the inwardly tapered or cone-shaped spools 110

17. The sleeves 16 and the ends of the roller 15 are mounted in journal boxes 18, which may be adjusted to effect the tightening of the apron by means of the set-screws 19, 5 which are in threaded engagement with said journal boxes and rotatably carried by the housing in such a manner as to prevent their longitudinal movement.

20 designates cables wound around the 10 sleeves 16 and connected therewith, and their opposite ends are connected with a support 21, in which is rotatably mounted a roll 22. The support 21 is provided with a stem 23, which is freely rotatable in a 15 bearing 24, which may be vertically adjusted by means of a screw 25. A set-screw 26 maintains the parts in their adjusted positions.

27 designates a belt tightening roll which 20 is journaled in brackets carried by the housing. The feed apron 14 also passes over a blade 28 adjustably carried by the housing of the machine.

29 designates a roll, which is located out 25 of axial alinement with the first or upper ironing roll 12, and said roll 29 is mounted in journal boxes 30, having depending rods 31 guided in apertures in the housing, Figs. 7 and 8. The rods 31 are provided with 30 apertures 32 into which extends rods 33, which carry at their lower ends rollers 34. Interposed between shoulders on the rods 33 and the lower ends of the rods 31 are 35 springs 35 which maintain said rollers in engagement with cams 36, which are mounted on a cam shaft 37 and may be manually adjusted by means of the handle 38 to vary the distance between the lower roll 29 and the upper ironing roll 12. These rolls 12 40 and 29 are intergeared by means of a gear 39 on the shaft of the roll 12 and a gear 40 on the shaft of the roll 29. The forward portion of the housing is provided with a 45 table 41 which serves as a support for the collars which are to be placed by the operator on the feed apron 14.

The shaft 8 also has mounted thereon a gear 42, which meshes with a gear 43 carried by the main ironing drum or cylinder 50 44, which is mounted on a shaft 45, journaled in the bearing boxes 46. The latter are carried by posts 47 which carry at their lower ends the rollers 48, Figs. 2 and 3, seated on cams 49, on a shaft 50. The shaft 55 50 has fixed thereto a worm wheel 51, which meshes with a worm 52 carried by a shaft 53 journaled in the housing and provided with a lever 54 which is adapted to be manually operated in order to effect the raising 60 or lowering of the main ironing drum 44. The posts 47 are guided in the machine framework.

Coöperating with the ironing cylinder or drum 44 are a plurality of sets of ironing rolls, any desired number of which may be 65

employed, and for convenience of illustration I have shown three sets 55, 56, and 57, respectively, and since each set is constructed and operated in a similar manner, I have deemed it unnecessary to describe in detail 70 but one of such sets. See Fig. 5.

58 designates sleeves carried by the housing in any desired manner and provided with apertured partitions 59 through which extend the rods 60. The outer ends of such 75 rods are provided with nuts 61 in threaded engagement therewith and contacting with washers 62, between which and the partitions 59 are interposed the springs 63, and since the washers 62 are adapted to move 80 into the lower chambers of the sleeves 58, a tension is placed on the rods 60, which tends to move them inwardly with respect to the sleeves. The rods 60 are in threaded or other engagement with the stems or posts 85 64, which are guided in the upper portions of the sleeves 58 and each post 64 has journaled therein the ends of a central ironing roll 65. The posts 64 are recessed at their upper ends at 66 and 67 to receive the 90 springs 68 and 69 respectively. 70 designates journal brackets pivotally connected at 71 with the upper portions of the posts 64.

72 designates an outer ironing roll journaled in the brackets 70 which are recessed 95 as at 73 in order to receive the springs 68 which abut against plates 74 located in the recesses 73 and carried by rods 75 in threaded engagement with the bearing, whereby the tension of said springs 68 may be varied, 100 as desired.

76 designates bolts passing freely through apertures 77 in the bearing brackets 70 and in threaded engagement with fixed portions of the posts 64, and the inner ends of such 105 bolts are provided with lock nuts 78. 79 designates a bearing bracket located on the side of each post 64 opposite to the bearing bracket 70 and pivotally connected at 80 with the upper end or head of the post 64. 110 The bearing brackets 79 have journaled therein an outer ironing roll 81 and are recessed as at 82 to receive one end of the springs 69, which abut against the plates 83 located within such recesses and carried 115 by rods 84 in threaded engagement with the bearing brackets 79, whereby the tension of the springs 69 may be varied, as desired.

85 designates bolts passing freely through the bearing brackets 79 and in threaded engagement with the upper ends of the posts 64 and provided with lock nuts 86.

In order to prevent the curling of the collars as they are fed to the first roll 72, I provide a gravity roll 87, Figs. 1 and 2, the 125 ends of which are free to move vertically in the slotted brackets 88 carried by the housing of the machine. 89 designates a receiving table carried by the housing in any desired manner and having one edge terminat- 130

ing in close proximity to the cylinder 44 and its opposite end is normally closed by a pivoted door 90.

91 designates steam conduits by means of which steam is circulated through the cylinder 44, and 92 designates similar steam conduits by means of which steam is circulated through the first ironing roll 12.

The shaft 45 has mounted thereon a gear 10 93 which meshes with gears 94 mounted on the shafts of the rolls 72, 65, and 81 of each set, so that said rolls revolve in unison with the drum 44. The rolls 72, 65 and 81 are, in practice, preferably covered with padding and fabric. The stems 95 of the journal boxes 13, which carry the ironing roll 12, are slidably mounted in the housing at an angle to the rods or stems 31 of the journal boxes 30 and preferably at substantially right angles to each other, as shown. The amount of axial displacement of the shafts of the rolls 12 and 29 may be varied by actuating the adjusting screws 96 and the set screws 97.

25 The operation of my novel ironing machine will now be readily apparent to those skilled in this art and is as follows:—

Assuming that the various parts of the machine are in their properly adjusted positions, the motor 2 is started. This causes the gear 3 to revolve and thereby the gears 4, 6 and 7, which effect the revolution of the sprocket wheel 9 and thereby actuates the sprocket chain 10, which latter imparts rotation to the ironing roll 12. Since the ironing roll 12 is intergeared with the roll 29 and is in frictional engagement with the belt 14, which passes between said ironing roll and the roll 29, a forward feeding movement is imparted to the feed apron 14. The gear 42 which is mounted on the same shaft 8 on which the sprocket wheel 9 is mounted, meshes with the gear 43 and thereby revolves the drum 44. The collars, after being washed, are treated with starch in any desired manner and are in condition to be ironed.

The operator arranges the collars to be ironed transversely with their bottom or inner face uppermost on the apron 14. The collars are fed by the feed apron beneath the first ironing roll 12 in parallelism with its axis and since this roll is out of axial alignment with the roll 29, substantially the entire under surface of the collar is brought into engagement with the ironing surface of the roll 12 and the entire inner surface of the collar is ironed, since it engages with a sufficient portion of the periphery of the ironing roll 12 to effect this result. If the roll 29 and the ironing roll 12 were in axial alignment, substantially only a line contact would be made with the collars to be ironed.

After the collar passes beyond the ironing roll 12, it travels beneath the gravity roll 87

and is delivered to the ironing cylinder 44 in parallelism with the axis thereof, and then passes first beneath the ironing roll 72, then beneath the ironing roll 65, and then beneath the ironing roll 81 of the first set 70 of rolls 55 in parallelism to their axes. The collar then passes beneath the subsequent sets of rolls in parallelism to their axes and is stripped from the drum 44 by the juxtaposed edge of the receiving table 89 and is 75 discharged on to said table. The collars are then passed through a seam dampening machine and then through a machine which turns the collar down and dries the edge. The collars are then ready to be sorted and 80 wrapped up for delivery to the owners.

I provide means to maintain the feed apron 14 in aligned position. If the apron 14 rides up on a spool 17 at one side of the machine, the adjacent cable 20 is wound up on 85 the sleeve 16, thereby moving the journaled support 21 with which it is connected, rearwardly, and thus moving the roller 22 on its fulcrum. This causes the feed apron to be returned to its proper position, and as 90 soon as the feed apron disengages from a cone 17, the tension roll 22 assumes its normal position, seen in Fig. 1.

Special attention is directed to some of the novel features of my invention. 95

The journal of the first ironing roll 12 is adjustable at right angles to the direction of movement of the roll 29, which, it will be understood by reference to Fig. 2, is yieldingly mounted. By such construction, the 100 axial displacement of the rolls 12 and 29 is permitted, so that a greater portion of the periphery of the ironing roll 12 is brought into direct contact with the feed apron 14 and with the collars passing therethrough 105 and since these collars are fed in parallelism with the axis of the ironing roll 12, the entire surface of the collar is simultaneously ironed.

Each set of ironing rolls which coöperate 110 with the cylinder 44 is yieldingly mounted, it being seen that any desired tension may be placed on the post 64 which carries the outer ironing rolls 72, 65 and 81 of a set.

The ironing rolls 72 and 81 are each provided with an adjustable tension device whereby any desired tension may be maintained on said rolls with respect to the cylinder 44. A tension of any desired degree is also maintained on the ironing rolls 65, 120 By such construction, a uniform tension is maintained on all the ironing rolls which coöperate with the main cylinder or ironing drum, so that during the ironing operation, a uniform pressure is placed on the 125 collars and the rolls are automatically adjusted so that a two ply collar and a collar of a greater number of plies are ironed with an equal degree of success without necessitating any adjustment of the parts. 130

1
The collar is fed in a flat condition laterally or in parallelism with the axes of the ironing drum and smaller rolls and is wholly exposed and uncovered. The direction of the feeding movement is continuously forward and not reciprocating and both surfaces of the collars are ironed in a single passage through the machine, thereby enabling one to obtain a greater economy in both time and labor and a greatly improved result.

In the machines of this general character as heretofore constructed, the natural spring inherent to a collar has been destroyed, since if sufficient pressure was placed on the small rolls to produce the proper action on the portion of the collar of uniform thickness, too great a pressure was placed on the collars at the seams where the collar is of increased thickness and the surface of the collar was not uniformly polished. In prior machines due to the facts that the axes of the small rolls were at too great a distance apart and the variation in the thickness of padding on the rolls, it was impossible to feed the collars through the machine in parallelism with the axis of the ironing rolls. In accordance with my present invention, the axes of the small rolls are brought close enough together to cause their peripheral portions to engage the collars when fed transversely and cause them to travel through the machine.

In so far as I am aware, I am the first in the art to feed a collar transversely instead of longitudinally in this manner, without clamping it to the feed apron and covering up portions of the collar, so that a subsequent ironing is necessary for such covered portions after the collar is removed from the machine, and it is to be understood that my claims to such features are to be interpreted with corresponding scope.

If the axes of the rolls of each set are not sufficiently close to each other, a collar will not feed up the high side of the drum and as the collar passed beneath the rolls of the last set of rolls, it would slide downwardly on the drum and stick to the collar in advance of it, so that the collars would not be properly ironed.

It will be evident that in the broad and generic scope of my invention, the collars pass through the machine with their longitudinal axes substantially in parallelism with the ironing rolls, and means are provided to effect the cyclical operation of the ironing mechanism and the parts co-operating therewith.

It will now be apparent that I have devised a novel and useful ironing machine, which embodies the features of advantage enumerated as desirable in the statement of the invention and the above description, and while I have, in the present instance, shown and described a preferred embodiment there-

of which will give in practice satisfactory and reliable results, it is to be understood that the same is susceptible of modification in various particulars without departing from the spirit or scope of the invention or 70 sacrificing any of its advantages.

Having thus described my invention, what I claim as new and desire to secure by Letters Patent, is:—

1. An ironing machine comprising an 75 ironing drum, a plurality of rolls opposed to the periphery of the drum, one of said rolls being movable relative to the other, yielding means for holding said rolls under pressure against the periphery of the drum, 80 and other yielding means for holding said relatively-movable roll under pressure against the periphery of the drum.

2. An ironing machine comprising an ironing drum, a set of three rolls opposed 85 to the periphery of the drum; the outer of said rolls being movable relative to the intermediate roll, yielding means for holding said rolls under pressure against the periphery of the drum, and other yielding 90 means for holding the outer and relatively-movable rolls under pressure against the periphery of the drum.

3. In an ironing machine, an ironing drum, sets of rolls mounted in proximity to 95 said drum, each set including stems, tension devices for the stems, a roll journaled in the stems, rolls pivotally carried by said stems and tension devices to move the pivotally mounted rolls toward said drum, in combination with means to revolve the rolls and drum, and means to feed articles to be ironed to the drum and rolls.

4. In an ironing machine, a yieldingly mounted roll, an ironing roll mounted in 105 proximity to said yieldingly mounted roll, means to revolve said rolls, mechanism to feed articles to be ironed to said rolls, and means to effect the axial displacement of said rolls to vary the effective ironing area of the 110 ironing roll.

5. In an ironing machine, the combination of an ironing drum, a roll opposed to the periphery thereof, an ironing roll spaced from the first-named ironing roll, means for 115 supporting the bight of a feed apron at a point adjacent to the periphery of the first-named ironing roll; said means being arranged in a horizontal plane intersecting the second-named roll, a roll opposed to the sec- 120 ond-named ironing roll and arranged as a whole at the opposite side of the vertical center thereof, with reference to the said bight-support, means back of the second-named ironing roll and the roll opposed 125 thereto for supporting a feed apron, and the said feed apron passed around the bight-support and the last-named means and between the second-named ironing roll and the roll opposed thereto.

6. In an ironing machine, the combination of a frame, an ironing roll mounted in the frame, a roll opposed to the ironing roll, rods carrying the second-named roll and guided in the frame and having sockets, rods disposed in said sockets and having shoulders, springs surrounding said rods and interposed between the shoulders thereof and the first-named rods, and a shaft mounted 5 in the frame and having cams opposed to the second-named rods and also having a handle.

7. In an ironing machine, intergeared rolls, one of which serves as an ironing roll 15 to iron one side of an article to be ironed, a feed apron passing between said rolls to support said article, driving means for one of said rolls, means to effect the axial displacement of said rolls to vary the effective 20 ironing area of the ironing roll, an ironing drum to which the article is fed by said apron and adapted to iron the other side of the article, outer rolls yieldingly mounted relative to said drum, and means to revolve 25 said drum and outer rolls.

8. An ironing machine, comprising in combination, a feed apron, a roll pivoted to move in a lateral plane and engaging the apron, a second roll around which the apron 30 passes, spools rotatably carried by said rolls and on which the apron rides when out of alinement, cables fixed to the spools and the first roll, a drum to which a collar is fed by said apron, rolls yieldingly mounted with 35 respect to said drum, and means to effect the operation of said rolls and drum.

9. In an ironing machine, an ironing drum, stems, rolls carried by the stems, journal brackets pivotally carried by said stems, 40 rolls mounted in said journal brackets, resilient means to move said rolls toward said drum, and means to actuate said ironing drum.

10. In an ironing machine, an ironing 45 drum, a plurality of stems yieldingly mounted about the periphery of the drum, rolls journaled in the stems, journal brackets movably carried by the stems, rolls mounted in said journal brackets on opposite sides of 50 said stem rolls, and springs between said stems and journal brackets.

11. In an ironing machine, the combination of an ironing drum, radially-movable stems having recesses, a roll mounted in said 55 stems and opposed to the periphery of the drum, means for yieldingly pressing the stems toward the center of the drum, brackets pivoted to the stems and having recesses opposite those of the stems, springs disposed 60 in said opposed recesses, a roll mounted in said brackets, and means for limiting the movements of the brackets relative to the stems.

12. In an ironing machine, a housing, an 65 ironing roll mounted therein, sleeves carried

by said housing, a stem in said sleeve, a tension device for said stem, means to vary the tension of said tension device, a roll journaled in said stem, journal brackets pivotally mounted on opposite sides of said 70 stem, rolls mounted in said journal brackets, said stem and brackets having alined recesses, springs in said recesses to effect relative movement of the brackets and stem and to move the rolls in the journal brackets 75 toward the ironing drum, means to vary the action of said spring, means to limit the relative movement of said stem and brackets, and means to rotate said ironing drum.

13. An ironing machine comprising sets of rolls arranged in a generally circular series and spaced relation; one roll in each set being movable relative to an adjacent roll, an ironing drum, the periphery of 85 which is opposed to said rolls, means for adjusting the drum toward and from the rolls, yielding means complementary to each set of rolls for holding the same under pressure against the periphery of the drum, and 90 other yielding means complementary to each set of rolls for holding the relatively-movable roll of the set under pressure against the periphery of the drum.

14. An ironing machine comprising in 95 combination a feed apron, a roll around which the apron passes, a roll engaging the apron and movable laterally, and means on the first-named roll actuatable by the apron when the latter gets out of alinement and 100 connected with the second-named roll to move the roll and restore the apron to alinement through the medium of said roll.

15. An ironing machine, comprising an ironing drum, sets of rolls opposed to the 105 periphery of the drum and arranged in spaced relation and sufficiently close together to enable the peripheral surfaces of two rolls to simultaneously engage a transversely fed collar; one roll in each set being movable relative to an adjacent roll thereof, yielding means complementary to each set of rolls for holding the same under pressure against the periphery of the drum, other yielding means complementary to each 110 set of rolls for holding the relatively movable roll of the set under pressure against the periphery of the drum, and means for feeding a collar to said rolls and drum in a flat and wholly uncovered condition and 115 in parallelism with their axes.

16. An ironing machine, comprising an ironing drum, sets of rolls opposed to the periphery of the drum and arranged in spaced relation and sufficiently close together to enable the peripheral surfaces of two rolls to simultaneously engage a transversely fed collar; each set of rolls including three rolls and the outer of said rolls being movable relative to the intermediate 125 130

roll, yielding means complementary to each set of rolls for holding the same under pressure against the periphery of the drum, other yielding means complementary to each set of rolls for holding the outer rolls under pressure against the drum, and means for feeding a collar to said rolls and drum in a flat and wholly uncovered condition and in parallelism with their axes.

10 17. In an ironing machine, the combination of an ironing drum, means for holding work to the periphery thereof, an ironing roll arranged parallel to and spaced from the drum, a roll opposed in parallel rela-

tion to the ironing roll and arranged entirely at the opposite side of the vertical axis thereof, with reference to the drum, and a suitably supported feed apron having a stretch disposed between the ironing roll and the roll parallel thereto and also having a portion extending to the drum and terminating in a horizontal plane intersecting the said ironing roll.

ISAAC F. WILLEY.
